LIQUID DISPENSING APPARATUS

Alfred L. Grisé, Springfield, Mass., assignor to
Gilbert & Barker Manufacturing Company,
West Springfield, Mass., a corporation of
Massachusetts

Application January 2, 1942, Serial No. 425,392

1 Claim. (Cl. 221—95)

This invention relates to improvements in a liquid dispensing apparatus having a flexible hose. A filling station gasoline pump is the important example. The idea is to provide control means operable in a new way by the movement of the hose, for starting and stopping the pump. This will be disclosed by the accompanying drawing, as illustrative means.

In the drawing—

Fig. 1 is a sectional elevational view of a gasoline dispensing apparatus embodying the invention;

Fig. 2 is a detail view of parts; and

Fig. 3 is a detail view indicating the spring drum construction.

In the drawing a specific type of hose handling apparatus has been shown in connection with a well-known form of gasoline dispensing "pump." Such pump is shown as embodying the extensible hose handling apparatus shown in the Hope Patent No. 2,225,271, dated December 17, 1940. However, this serves as an illustrative example only, since it will be recognized that the device of my invention may be adapted to other forms of hose handling equipment in connection with pump apparatus. It is not intended that the invention be limited to the particular extensible hose handling structure of said prior patent.

The various operative elements necessary for dispensing the liquid through the system are shown in Fig. 1, and it will suffice here to trace the flow of liquid from the inlet of the pump to its outlet. The fluid is first drawn up from an underground tank (not shown) through suction pipe 1 by a pump 2, (driven by an electric motor 3), and is then forced by the pump through a discharge line 4 to air separator 5. From the air separator 5 air-free liquid passes through a meter 6, (which drives a register 7 by means of a shaft 8), then through a pipe 9 to the flexible hose 10 and valve-controlled nozzle 11. All these parts are generally known, all being suitably housed in a casing, except for the dispensing nozzle and its connection through the casing, two walls of which are shown by the numbers 12.

The flexible hose 10 in this structure as illustrated hangs in two loops—one hangs outside the casing in the usual manner with the nozzle 11 placed on the support 13; the other, connected with the outside loop by a section of the hose passing across the top of the pumping means, hangs inside the casing and passes around a sheave 14 adapted to rise and fall

within a narrow well formed by one casing wall 12 and a sheet of metal 14' attached for that purpose to supporting posts 15 of the "pump" standard. The inside loop is only used in instances when more than the ordinary length of hose is required to reach a point at which delivery is desired. The outside loop alone, as pointed out in said previously mentioned Hope patent, will suffice to serve an area effective for most deliveries.

The flow controlling mechanism will now be described with reference to Fig. 1. A control lever 16 mounted on a shaft 13' extending through the nozzle support 13 as indicated, is in "off" position when nozzle 11 is hung on the support. The nozzle handle guard blocks lever 16 from turning to "on" position. The lever 16 governs a rod 17 which slides freely in a vertical hole 18, see Fig. 2, in one end of a switch arm 19. Arm 19 is pivoted in the middle on a switch box 21. A stop collar 20 on rod 17 contacts one end of the arm 19 when the control lever 16 is in "off" position, as in Fig. 1, and prevents the switch arm 19 from being turned clockwise and thereby prevents closing the circuit of the switch in box 21. Box 21 is attached to motor 3 and the switch controls the running of the motor. No detail of the electrical connections is shown here as the switch and motor arrangement per se is well known in the art and widely used. The novelty in my arrangement has to do with the means and circumstances of operating the switch.

When the nozzle is taken off its hook support 13 and the control lever 16 is moved to "on" position (by counter-clockwise movement), the rod 17 is moved upwardly (by a lever arm, the near end 16' of which is shown in Fig. 1 attached to shaft 13', the far end of which moves upwardly while engaging rod 17). Rod 17, sliding freely in the vertical hole 18 at the end of switch arm 19, carries the stop collar 20 away from contact with arm 19 (see Fig. 2). The apertured end of arm 19 is then free to move upwardly and operate the switch 21 to close the circuit and start the pump motor.

The mechanism for actuating the switch arm 19 when the stop collar 20 is raised is connected with that end of switch arm 19 opposite the apertured end. This end is bifurcated for a purpose to be presently described. Two stop pins 22 and 23 above and below arm 19 are arranged to limit its movement.

Adjacent the switch box 21 on shaft 30 is mounted a spring drum 24 with a cable 25 wound

thereon, see Figs. 1 and 3. The cable 25 has one end suitably attached to the drum 24, is wound around it and extended upwardly to a roller 26 mounted on the casing wall below the opening through which hose 10 extends to the outside loop. The cable then passes through an opening in the wall to the outside and running through a guide collar 27 on hose 10 it is attached to a bridle clamp 28, also affixed to hose 10.

The spring drum is provided with a boss 29 which is suited to drive by frictional contact a tripping arm 31 mounted on shaft 30. The tripping arm extends between the prongs at the bifurcated end of switch lever arm 19 and is capable of moving that end of arm 19 up or down within the limits imposed by stops 22 and 23.

It will be seen from the above description that as the cable is unwound from the drum 24 the rotation of the drum will cause the tripping arm 31 to move in a counter-clockwise direction. The end of arm 31 will then move the bifurcated end of switch arm 19 down or clockwise. This turning of arm 19 will close the switch and start the pump motor. When the circuit has closed, stop 22 will hold arm 31 from rotating further in that direction, since arm 19 has reached the limit of its movement. This "on" position is indicated in Fig. 2. The cable may be unwound further than enough to close the switch and this continued rotation of drum 24 will not move arm 31. A frictional contact only exists between boss 29 and arm 31.

When the unwinding movement of cable 25 stops, the spring 34 in the drum will begin to rewind the cable and thus turn the drum in a reverse or clockwise direction unless something prevents such operation. This operation, when permitted, will carry the tripping arm 31 in contact with arm 19 in an upward direction or a counter-clockwise turning of arm 19. The switch will then open and the stop 23 will effectively resist any further motion of arm 31.

It will be recognized that in the same manner as stops 22 and 23, stop 20 resists rotation of arm 19. Thus, until control lever 16 is in "on" position with stop 20 raised as in Fig. 2, rotation of drum 24 and arm 31 will have no effect on arm 19. As indicated in Fig. 1, the nozzle support 13 when it supports the nozzle by the handle guard, provides for blocking the movement of lever 16 and thus stop 20 to "on" position.

In operation the device works as follows: The nozzle is taken off its support and the lever 16 is turned to "on" position. The operator carries the hose to the point where delivery is desired. He is exerting no tension on the hose beyond that necessary to lift and carry it. As this is done, the hose, which has been hanging vertically in a loop on the outside of the casing, then tends to swing outwardly from the casing by a pivoting movement and carry the cable with it. The weight of the hose itself is enough to exert the tension necessary to withdraw cable 25. The

shift of the hose from vertical position to one at an angle causes cable 25 to turn the drum 24 and trip arm 19, stop 20 having been raised by lever 16. Thus, the motor starts the pumping system and dispensing can take place.

In case the outward swing is not enough, which would be the situation if it were not necessary for the operator to carry the nozzle away from the side of the pump to make his delivery, the operator can start the motor merely by raising the hose portion next the pump casing toward a horizontal position enough to operate cable 25.

With this construction, if during dispensing or after the operator carelessly leaves the hose unattended, the portion next the pump casing will drop back toward vertical position and thus permit the spring to rewind the slackened cable and shut off the motor.

It will be noted that structure disclosed is adapted to automatically start the motor without the need for the attendant doing more than carry the hose to the point of delivery. For all deliveries with the ordinary length of hose, the operator can ignore the existence of the reserve loop inside the casing without being called upon to pull out a certain length of hose to actuate the cable and its associated means. The cable is made of a length sufficient to allow extension of the hose 10 to its maximum length in the illustrated apparatus.

What I claim is:

In dispensing apparatus of the electric gasoline pump using a delivery hose with a loop normally hung on the outside ready for use and having means adapted to start and stop the pump which is automatically operated by movement of the hose nozzle to and from a point of delivery, the combination of a display casing, a delivery hose having a substantial portion of its length normally positioned inside the casing and another substantial portion normally hung as a loop for display outside the casing, an electric pump mechanism inside the casing having a starting and stopping switch, mechanism to open and close said switch, said mechanism comprising a switch-operating element, actuating means for said element made up of a drum-like member to store a long cable cord, a spring adapted to wind such cord on the drum-like member, a cord connected to tension said spring when unwound, said cord being connected to the hose portion normally outside the casing to cause its unwinding as said hose is moved for delivery, a friction drive between said switch operating element and said drum adapted to promptly open and close said switch as the drum is turned in one direction or the other, all adapted for said cord to operate with the hose for the purpose described, whether or not the outside portion is moved along or the inside portion is pulled out of the casing to reach the point of delivery.

ALFRED L. GRISÉ.
